SPOON OR SIMILAR ARTICLE

Ernest Frederick Thomson and Frederick Allen Burke,
New York, N. Y., assignors to R. Wallace & Sons
Manufacturing Company, Wallingford, Conn., a corpo-
ration of Connecticut

Application September 26, 1956, Serial No. 43,099

Term of patent 14 years

(Cl. D54—12)

FIG. 1

FIG. 2

FIG. 3

FIG. 4

FIG. 5

FIG. 6

Fig. 1 is a front view of a spoon showing our new design;

Fig. 2 is a rear view thereof;

Fig. 3 is an edge view thereof;

Fig. 4 is a section taken on line 4—4 of Fig. 1;

Fig. 5 is a section taken on line 5—5 of Fig. 1; and

Fig. 6 is an enlarged fragmentary view of the portion of the handle shown between dot and dash lines of Fig. 1.

We claim:

The ornamental design for a spoon or similar article, substantially as shown.
